(57) **CLAIM**

We claim the ornamental design for a bottle, as shown and described.

DESCRIPTION

FIG. 1 is a right side view of a bottle showing our new design, wherein the left side is a mirror image.

FIG. 2 is a rear view of the bottle.

FIG. 3 is a top plan view of the bottle; and,

FIG. 4 is a bottom plan view of the bottle.

The broken lines shown represent unclaimed subject matter and form no part of the claimed design.
